UNITED STATES PATENT OFFICE.

DEWIS LANDAU, OF SAN FRANCISCO, CALIFORNIA, ASSIGNOR TO LANDAU ECONOMIC SIPHON COMPANY, OF SAN FRANCISCO, CALIFORNIA, A CORPORATION OF CALIFORNIA.

SIPHON.

No. 893,850.

Specification of Letters Patent.

Patented July 21, 1908.

Application filed December 10, 1906. Serial No. 347,213.

To all whom it may concern:

Be it known that I, DEWIS LANDAU, a citizen of the United States, residing at San Francisco, in the county of San Francisco and State of California, have invented new and useful Improvements in Siphons, of which the following is a specification.

This invention relates to improvements in siphon bottles and the like. It is well known that, in bottles of this character, when almost all of the liquid has been withdrawn from the receptacle, the gaseous pressure frequently becomes so low that it is impossible to force out, by means of said pressure, the residue of the liquid, and consequently the receptacle is not completely emptied. To avoid this result, it is customary to charge the bottle at a higher pressure than would otherwise be necessary. But this unduly high pressure has been the cause of many fatalities, owing to the bursting of the bottle. One object of the present invention is to provide means whereby this defect can be avoided.

A further object is to provide a bottle of this character having an improved air relief which will tend to prevent the air relief passage remaining open after the charging of the siphon has been completed.

A further object is to provide a bottle of this character which can be more easily and conveniently cleaned than heretofore.

In the accompanying drawing, Figure 1 is a broken side elevation of a siphon bottle equipped with my invention; Fig. 2 is a similar view taken at right angles to Fig. 1; Fig. 3 is a view similar to Fig. 1 of a modified form of the invention; Fig. 4 is a detail side view at right angles to that of Fig. 3; Figs. 5 and 6 are views similar to Figs. 3 and 4 of a modified form of the invention.

Referring to the drawing, 1 indicates the receptacle for the liquid, provided in the usual manner with a siphon tube 2. 3 indicates the metallic head of the siphon bottle, formed with a filling tube 4, whereby the siphon can be charged with aerated liquid from a charging apparatus 5. The construction of these parts is, in general, similar to that shown in my United States Patents Nos. 801,831, dated April 23, 1905, and 816,985, dated August 1, 1905, and need not here be further specified. The siphon head is also formed, at the opposite side to the charging tube, with a discharge spout 6, a valve 7, and valve operating mechanism 8,

all similar to those disclosed in my U. S. Patent No. 791,628, dated May 25, 1904, the location, however, of this part of the mechanism being different from that shown in said patent.

The reason for changing the location of the discharging mechanism, is to permit of the addition of my improvement, which I will now describe in detail. Upon the top of the siphon head is screwed a vertical pump cylinder 9, in which reciprocates a plunger 10 operated by a hollow handle 11. Said cylinder connects with the interior of the siphon through an aperture 12 in the upper wall 13, said aperture being normally closed by means of a valve 14 and a spring 15, around the stem of said valve, and pressing against a plate 16 upon the end of said stem. A valve 17 closes the entrance to the hollow stem when the plunger is descending, and is opened when the plunger is ascending to admit air into said pump chamber.

When nearly all of the liquid has been drawn off from the receptacle 1, and the gaseous pressure consequently becomes too low to force out the residue of the liquid, the pressure may be increased by operating the pump, thereby admitting air from the exterior into the pump chamber, and, when the air is sufficiently compressed, forcing it downwards through the aperture 12, causing the valve 14 to open against the pressure of the spring. By this means the gaseous pressure is sufficiently increased to expel the residue of the liquid from the siphon. A further advantage of this construction is that it is no longer necessary to charge the siphon originally at a high pressure in order to have sufficient pressure to expel the residue of the liquid, when nearly empty. This high pressure has been the cause of many fatal accidents, all of which are avoided by this improvement.

My invention also includes improved means for permitting the escape of compressed gas from the liquid. It is desirable that the air relief should not remain open longer than is necessary for the charging of the siphon, and for this purpose, I have provided a construction which necessitates the use of the charging apparatus to maintain said air relief open, so that, upon the removal of the charging apparatus, the air relief automatically closes. This mechanism comprises a valve 20 operated by a spring 21 inclosing the

air relief opening 22, said valve having a stem 23 extending through said opening and terminating in a pointed end 24. Said end being pointed is not adapted to be pressed inwards by the finger to open the air relief, and, for the purpose of so opening it, there is provided a metallic presser piece 25, which is attached to, and suspended from, an arm 26 of the charging apparatus. When said charging apparatus is in position, said presser piece is also in such position that its end can be applied to the pointed end of the valve stem to press said valve inward and open the air relief. But as soon as the charging apparatus is removed, the presser piece is necessarily removed with it, and the air relief closes.

In Figs. 3 and 5, I have shown a modified form of pump, the plunger stem in this case being operated by means of a slotted lever 27 engaging a pin 28 on the side of said stem. It is understood, however, that any form of pump may be used. In these figures also a different dispensing apparatus is shown from that shown in Figs. 1 and 2, namely, that disclosed in my U. S. Patent No. 835,442, dated May 31, 1906.

In Figs. 3, 4, 5, and 6 an improved form of siphon bottle is shown. Siphon bottles as at present constructed are difficult to clean. They need washing out occasionally, and this, with their present construction, is a difficult task, requiring special tools and experienced men to open the bottle. By my improvement this difficulty is avoided. For this purpose, the siphon head shown at 31 in these figures, is detachable, and in order to clamp the head in position, I use the ordinary form of wire yoke-lever clamp 33 commonly used for milk bottles, beer bottles, and the like. In Figs. 3 and 4, the levers are attached to the head by means of a yoke-shaped piece of wire 34 which engages lugs

35 cast upon said head, said piece 34 passing half way round said portion, and its ends being hooked into the loops 36 of the yoke lever 33. In Figs. 5 and 6, there is provided a collar 30 attached to the glass portion of the bottle in the usual manner, and said yoke lever 33 is connected with said head by means of the hooked links 37. A rubber washer 32 is interposed between the head and the glass bottle or the collar 30. It will readily be seen that, with this construction, the metallic siphon head, carrying with it the siphon tube, can be readily withdrawn for washing the bottle and as quickly replaced in position, by any person, no experience being necessary. The rubber washer prevents any leakage at the juncture of the parts so separated.

I claim:—

1. A siphon bottle having means located at the side of the bottle for charging the siphon from a separate charging apparatus, and means for independently charging the bottle to increase the gaseous pressure, said means comprising a vertical pump cylinder, a plunger adapted to reciprocate in said cylinder, and a valve for admitting compressed air from said cylinder into the siphon bottle, substantially as described.

2. A siphon bottle having an air relief comprising a valve for closing the air relief passage, and having its outer end sharply pointed to prevent pressure on the same by the finger to actuate the relief valve, substantially as described.

In testimony whereof I have hereunto set my hand in the presence of two subscribing witnesses.

DEWIS LANDAU.
